UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING CLAMPING AND PARTING MECHANISM FOR LOOMS.

1,418,472.

Specification of Letters Patent. Patented June 6, 1922.

Application filed September 23, 1921. Serial No. 502,663.

To all whom it may concern:

Be it known that I, ALONZO E. RHOADES, a citizen of the United States, and resident of Hopedale, county of Worcester, State of Massachusetts, have invented an Improvement in Filling Clamping and Parting Mechanism for Looms, of which the following description, in connection with the accompanying drawing, is a specification, like characters on the drawing representing like parts.

This invention relates to automatic filling replenishing looms wherein the running filling is replenished prior to complete exhaustion and wherein the old or spent filling is parted between the cloth and the shuttle by parting means mounted upon a carrier, such as the usual swinging shuttle feeler, so as to be moved bodily, rearwardly and forwardly or toward and from the lay. The object of the invention is to provide an improved simple and effective means for operating the filling clamping and parting device when, and only when, a fresh filling carrier is transferred from the magazine or supply to the lay.

The object of the invention is further to provide a construction which may be readily adapted to existing looms.

30 The object of the invention is further to provide a construction which will yield upon the occurrence of an abnormal resistance to the operation of the filling, clamping and parting device.

35 The object of the invention is further to provide a construction which eliminates the necessity of special accuracy in the assembling, positioning and adjusting of the filling, clamping and parting mechanism.

40 The object of the invention is further to provide a construction in which the parts are readily positioned so that when the movable cutter blade is actuated to close the filling, clamping and parting device no injurious strain is placed upon the parts after the closing position has been reached.

These and other objects and features of the invention will appear more fully from the accompanying description and drawings and will be particularly pointed out in the claims.

In the drawings:

Fig. 1 is a transverse section of a portion

of an automatic filling replenishing loom with a preferred form of the present invention embodied therein;

Fig. 2 is a detail in front elevation and partially in vertical cross section with the filling clamping and parting device in its rearward position.

The construction above stated is that of the well-known Northrop type of automatic filling replenishing loom and as this construction is familiar to those skilled in the art no detailed illustration or description beyond the features particularly concerned with this invention is necessary.

The broad feature of insuring the operation of the filling clamping and parting means when, and only when, a fresh filling carrier is transferred from the magazine to the lay is disclosed in the patent to Davis, 1,084,878 granted January 20, 1914 and a further construction embodying this broad feature and to which the present invention is subsidiary is disclosed in the application of Edward S. Stimpson No. 469,509 filed May 14, 1921. The patent to Davis serves to illustrate the general type of mechanism in connection with which the preferred form of the present invention is herein illustrated.

In the present invention a rigid actuator or actuator lever is provided for effecting the closing movement of the filling clamping and parting device. This actuator is permanently connected to the usual filling carrier support which yields and supports and guides the filling carrier as it passes from the magazine to the lay, so that the actuator is moved when, and only when, a fresh filling carrier is transferred. The yielding feature which characterizes the invention is provided in this invention by a spring connected to the actuator lever and to a fixed part of the loom such as the hopper or magazine stand. Under normal conditions this spring is rigid but upon the occurrence of abnormal resistance to the operation of the filling clamping and parting device this spring yields or extends thus securing the desired results.

A simple adjustment is provided between the parts of the actuator lever which permits of the ready assembling and adjustment of the entire mechanism including the filling clamping and parting device. The perma-

ment attachment of the actuator lever to the filling carrier support insures at all times its accurate position.

With this general understanding a brief 5 description of the construction will be sufficient.

The lay 1; the transferrer 2 which upon the call for filling replenishment acts to transfer the fresh filling carriers, or in this 10 case the bobbins 3 from the magazine or hopper 4 to the lay, or in this case to the shuttle 5, at the replenishing side of the loom; the controller rocks shaft 6 which is rocked upon the indication of substantial 15 exhaustion in the running shuttle and acts to initiate filling replenishment; the breast beam 7; the shuttle feeler arm 8; which rocks and slides on the stud 9, being swung over the lay in front of the boxed shuttle 20 upon the operation of the controller rock shaft 6 and returned under the action of the spring 10 are parts the construction and operation of which will be readily understood by one familiar with the art, such as is dis- 25 closed in the patent to Davis above mentioned and the patents therein referred to.

The replenishing magazine is provided with the usual guide stop 11 against which the filling carrier 3 is brought into position 30 for transfer. The filling carrier to be transferred is yieldingly supported and guided on the side opposite to the stop 11 by the usual movable filling carrier support 12 in the form of a flat finger located adjacent the 35 inner face of the magazine. This supporting finger 12 is connected to a stud 13 extending through the side of the magazine and carrying on the opposite side an arm 14. A spring 15 is held between a lug 16 on the 40 magazine and the head 17 of a slide rod 18 connected with the arm 14, the rod being guided in the lug. The stop 11 thus forms one side of a throat which the filling carrier passes through from the magazine to the 45 lay, the filling carrier support or finger 12 forming the other side. When the trans- 50 ferrer 2 is operated to transfer a fresh filling carrier from the magazine to the lay, this filling carrier support yields and supports and guides the filling carrier as it passes to the lay.

The filling clamping and parting device may be of any suitable form and construction and is shown as generally similar to that 55 illustrated in the patents above referred to. This device is also shown as supported and carried by the usual shuttle feeler 8.

The movable blade 19 co-operates with 60 fixed blades one of which is shown at 20 and the movable blade 19 secures its open- 65 ing and closing movement about the pivot 21.

When a replenishment of filling is called for the shaft 6 is rocked in the usual man- 70 ner raising the arm 22, extending rearwardly 65 therefrom, and therethrough rocking the

shuttle feeler 8 toward the lay. If the shuttle is properly boxed this feeler will pass in front of the shuttle in the usual manner and the lug 23 will be brought into the path of a bunter on the lay and thereupon the 70 transferrer 2 will be operated to transfer a fresh filling carrier 3 from the magazine to the lay there beneath.

When the shuttle feeler thus swings rear- 75 wardly over the lay the filling extending from the filling carrier to be abandoned enters between the members of the filling clamping and parting device which are then in open position as shown in dotted lines in Figure 1.

80 In the case of the type of mechanism to which this invention relates the filling clamping and parting device is closed to clamp and part the filling when, and only when, the filling carrier is actually trans- 85 ferred by the transferrer from the magazine to the lay. Consequently if the shuttle be improperly boxed so that it is struck by the shuttle feeler or if the conditions are such that the shuttle feeler no matter to what extent it may move does not effect a filling transfer, or if for any reason the filling transfer does not actually take place then there can be no severance of the filling by 90 the filling clamping and parting device. 95

In securing this result the present invention provides a yieldable actuator or actuator lever permanently connected to the filling carrier support and extended in position to effect the closing action of the filling clamping and parting device when it is in operative position and transfer takes place and the filling carrier support is moved. The fulcrum of this actuator lever 100 consists of a spring connected to a fixed part of the loom such as the magazine stand so that in case of any abnormal resistance there will be no danger of a smash or of damage to the loom. This construction also eliminates the requirement of any great nicety or accuracy in adjusting and positioning of the mechanism including the filling clamping and parting means so long as the parts are adjusted to insure the closing action of the filling clamping and parting means. Any 105 further movement which may take place 110 due to the adjustment or position of the parts will be taken up by the yield of the fulcrum spring of the actuator. The mechanism is readily applied to an existing loom 115 without alteration and is always in permanent position because of its connection to the filling carrier support. A simple adjustment is also provided by making the actuator lever in two parts adjustably connected.

120 In the construction illustrated the actuator or actuator lever comprises a generally horizontally extending bar 24, having a hub 25 pivoted on the journal stud 26 projecting from the arm 14 of the filling carrier sup- 130

port. At its forward end the bar 14 has a vertical rib and groove connection with a vertical bar 27 forming a part of the actuator lever. A stud 28 in the bar 24 passes 5 through a slot 29 in the bar 27 and is provided with a nut 30, thus enabling the parts of the actuator lever to be relatively adjusted. The lower end of the bar 27 which constitutes the forward end of the actuator 10 lever is provided with a laterally extending foot plate 31 inclined downwardly and forwardly and so adjusted and positioned that when the filling clamping and parting device moves to its rearward or operative position 15 with the blades in open position the pin 32 projecting laterally from the fixed blade 19 will pass and stand over this foot plate. The bar 24 of the actuator lever is fulcrumed at 33 on the lower end of a helical spring 34 hooked onto a stud 35 secured in a fixed part of the loom such as the magazine stand.

It will be seen therefore that if transfer takes place and the filling clamping and 25 parting means are in the position shown in dotted lines in Fig. 1 or in operative position the filling carrier support 12 will be rocked thus carrying the rearward end of the actuator lever downwardly. This rocks 30 the actuator lever about its fulcrum 33 and raises the forward end terminating in the foot plate 31 thus in turn raising the pin 32 of the movable member of the filling clamping and parting device and effecting the 35 clamping and parting of the filling. If, for any reason whatever, such as inaccuracy of adjustment, or abnormal resistance to movement of the parts the movement of the actuator lever continues after the filling clamping 40 and parting means have closed then the spring 34 will yield and thus no injury or damage will occur to any of the parts.

The opening movement of the filling clamping and parting device is effected by a 45 pin 36 projecting laterally from the blade 19 in connection with the usual switch cam 37 pivoted at 38 on the supporting arm 39.

There is thus provided a very simple and practical mechanism readily applied to existing looms, readily adjusted to existing 50

conditions and of strong and efficient construction.

Having thus described my invention what I claim as new and desire to secure by Letters Patent is:

1. An automatic filling replenishing loom comprising a lay, a replenishing magazine for the fresh filling carriers, means for transferring a fresh filling carrier from the magazine to the lay, a filling clamping and parting device movable into position to receive the running filling when the lay is in position for transfer, a movable filling carrier support moved by the filling carrier upon its discharge from the magazine to the lay, a spring connected at one end to the loom frame and forming at the other end a fulcrum support, an actuator lever pivoted at one end on the movable filling carrier support, fulcrumed on the said fulcrum support, and engaging at the other end the filling clamping and parting device when in rearward position whereby the said actuator lever is yieldable upon the occurrence of an abnormal resistance but acts under 75 normal conditions to actuate the filling clamping and parting device upon the movement of the filling carrier support to effect the clamping and parting of the filling extending from the filling carrier to be abandoned.

2. An automatic filling replenishing loom comprising the construction defined in claim 1 in which the actuator lever is constructed in two parts and provided with 80 means for adjustably connecting the said parts together.

3. An automatic filling replenishing loom comprising the construction defined in claim 1 in which the end of the actuator 90 lever is provided with a laterally extending foot plate and in which the movable member of the filling clamping and parting device is provided with a laterally extending pin arranged to stand above the foot plate 95 when the filling clamping and parting device is in rearward operative position.

In testimony whereof, I have signed my name to this specification.

ALONZO E. RHOADES.
